WASTE BASKET

Robert S. Beverlin, Toledo, Ohio, assignor to Globe-Wernicke Industries, Inc., Toledo, Ohio, a corporation of Ohio

Application September 29, 1958, Serial No. 52,798

Term of patent 14 years

(Cl. D58—4)

Fig. 1

Fig. 5

Fig. 2

Fig. 3

Figure 4 is an enlarged transverse fragmentary sectional view taken through the rim portion of the waste basket; and

I claim:

The ornamental design for a waste basket, as shown.
